UNITED STATES PATENT OFFICE

S. H. TIFT, OF MORRISVILLE, VERMONT.

APPARATUS FOR ELEVATING WATER.

Specification of Letters Patent No. 26,305, dated November 29, 1859.

To all whom it may concern:

Be it known that I, S. H. TIFT, of Morrisville, in the county of Lamoille and State of Vermont, have invented a new and useful 5 Improvement in Apparatus for Elevating Water; and I do hereby declare that the following is a full, clear, and exact description of the same, reference being had to the annexed drawing, forming part of this specification, in the several figures of which similar characters of reference denote the same part.

Figure 1 is a plan view of the water elevator. Fig. 2 is a vertical section of the 15 same on line x, x . Fig. 3, is a bottom view of one of the buckets with the trunnion attached.

This invention has reference to the raising of water from reservoirs or wells, by 20 means of an endless band, a series of buckets and a notched, flanged wheel, they being constructed and combined in the manner hereinafter to be set forth.

Its nature consists in having over the well, 25 a wheel with flanges on each side, said flanges being notched at regular distances. This wheel has its bearings in a frame extending down into the well, at the lower end of which frame is placed a roller also 30 having its bearings in it. Around this roller and wheel, and fitting between the flanges of the latter is an endless band composed of india rubber, gutta percha, or some similar substance, and to this band are attached the 35 buckets by an axle or trunnion fastened to the bottom of the buckets and passing through eyes on each side of the band, the ends of said trunnions resting in the notches of the flanges on the wheel.

40 The buckets are shaped as shown in Fig. 2 having the rear of the top curved, so that as each bucket empties its contents the curved rear of the preceding one serves as a chute to carry off the water into the trough 45 or receiver.

In the drawing W, is the flanged wheel, having notches n , in the flanges, and having its bearings in frame F; R, is the roller at the bottom of the frame, in the well; b , the endless band passing around wheel and 50 roller; B, the buckets attached to the band by trunnions T, fastened to the bottom of them, passing through eyes on each side of the band, and resting in the notches n , of the flanged wheel W; D, is the receiving 55 trough into which the buckets empty their contents.

The power is applied to shaft of wheel W, and by its revolution, that of band b , and buckets B, is produced the buckets filling 60 with water from the well and when they descend, discharge their contents into the receiver D, and through its spout.

The buckets being constructed as described with the curved rear, each one serves 65 as chute or guide for the contents of the following one to fall over into the receiver. And also the buckets being fastened to the band by the trunnions passing through eyes on it, and having their ends resting in the 70 notches in the flanged wheel, when the buckets come up filled with water the weight is thrown against the sides of the notches and thus prevents any strain or drag on the band.

75 Having thus described my improvement, I claim,

The buckets, B, curved at the rear as described, in combination with the trunnions, T, band, b , notched, flanged wheel, W, roller, 80 R, and frame, F, constructed and operating substantially in the manner and for the purpose set forth.

In testimony whereof I have hereunto signed my name before two subscribing witnesses.

S. H. TIFT.
